ELMER E. WELLS, OF STOCKTON, CALIFORNIA.

OILING ATTACHMENT FOR MOTOR-VEHICLES.

1,315,616.

Specification of Letters Patent.

Patented Sept. 9, 1919.

Application filed April 28, 1919. Serial No. 293,368.

To all whom it may concern:

Be it known that I, ELMER E. WELLS, a citizen of the United States of America, residing at Stockton, in the county of San Joaquin, State of California, have invented certain new and useful Improvements in Oiling Attachments for Motor-Vehicles; and I do declare the following to be a clear, full, and exact description of the same, reference being had to the accompanying drawings, and to the characters of reference marked thereon, which form a part of this application.

This invention relates to improvements in oil distributing devices for motor vehicles and particularly for those having the Ford type of engine.

The principal object of the invention is to provide a piping system adapted to be positioned outside of and alongside the engine and providing communication between a high point in the transmission casing and the lower forward end of the timer case, which is at the front end of the engine.

With the present system used and installed on engines of this type, the oil distributing tube extends from a point in the flywheel housing to a point behind the timer gears at the front end of the motor. This is an objectionable and disadvantageous feature, as I have found from experience, for when mounting a grade, the said gears and other parts close thereto fail to receive any oil and eventually run dry.

Also, on account of the small angle of slope forward of this tube, a relatively gentle grade will cause the tube to cease delivering any oil from the forward end thereof when the car is mounting such grade, and as a result, the forward bearings, pistons, etc., do not receive their necessary quota of oil and are apt to run dry and seize in the cylinders.

Another disadvantageous feature of the present system is one the reverse of that just described. This is, that no provision has been made for controlling or stopping the flow of oil to the forward end of the motor when the car is running down grade, a position which increases the relative angle of the oil tube to the horizon and causes a flood of oil to be deposited at the forward end of the motor.

This causes too great a quantity to be

splashed up into the forward cylinders, and the latter become foul and carbon deposits reform. This is especially so, as when traveling down grade, less fuel is being supplied to the engine and the resultant work being done thereby is not sufficient to absorb and utilize this amount of oil.

Another object of my invention therefore is to so install my device that a greater downward slant from the back to the front of the motor is had, which will allow the delivery of sufficient oil to the forward end of the motor even when climbing a considerable grade.

As a further object, I have interposed in the piping system an automatic means whereby the flow of oil therethrough will be shut off when the car is traveling down grade, thereby preventing the flooding and fouling previously mentioned.

A still further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a perspective outline of a gas engine of the Ford type showing my oiling attachment thereon.

Fig. 2 is an enlarged rear end elevation of that portion of the system projecting from the transmission casing.

Fig. 3 is a perspective elevation of an oil-catching trough.

Fig. 4 is a sectional view through an automatic ball check valve.

Referring now more particularly to the characters of reference on the drawings, the numeral 1 designates the motor having the usual transmission casing 2 at the rear end thereof and the usual timer-gear case 3 at the lower forward end of the same.

Positioned horizontally inside the casing 2 at a relatively high point therein is a trough 4 having an end wall 5 adapted to rest against the inside of the casing and conform to the curvature thereof. Projecting through and being threaded into the casing

and formed integral with the trough 4 is a nipple 6, whose lower level is that of the trough 4.

A sleeve 7 is adapted to thread over the 5 nipple and impinge against the outside of the casing 2 to lock the trough in place, this sleeve projecting beyond the nipple 6 to form a coupling for a pipe 8 adapted to abut against the end of the nipple 6.

10 The pipe 8 and the portion of the sleeve 7 enveloping the same are threaded with a pitch the reverse of that of the nipple 6, so that the sleeve 6 serves both as a union and a locknut. The outer end of the sleeve is of 15 hexagonal periphery, as at 9, in order to place a turning wrench thereon.

The pipe 8 beyond the sleeve bends down for a certain distance, as at 10, and has a T 11 interposed therein, which T has a nipple 12 projecting downwardly therefrom and being covered at its lower end by a cap 13. Into the outer end of the T 11 is threaded the male projection 14 of a ball-check T 15, the main portion of which is at right angles to 25 the pipe 8, that is, longitudinally of the motor 1, and has a normal downward slant to the rear, as shown in Fig. 4.

A ball 16 is positioned in the member 15 and is adapted to roll therein to contact with 30 a seat 17 formed in the forward end of the member 15. A plug 15^a is screwed into the rear end of the member 15, and the ball normally rests thereagainst, owing to the downward and rearward slant of the T. The purpose and function of this unit being a check valve, I will refer to it as such hereinafter.

Threaded into the check valve 15 at the end having the seat 17 is a pipe 18, extending at a suitable downward slant toward the 40 front end of the motor and with such bends therein as may be necessary, as at 19, in order to connect the same with the front end of the timer case 3, as shown in Fig. 1. Interposed in the pipe 18 at this point is a T 45 20 having a horizontal plug 21 therein so that with the removal of this plug the quantity of oil being delivered into the timer case may be seen at a glance.

In the operation of the device, the oil is 50 thrown into the trough 4 by the whirling of the gears in the transmission casing. From there it flows through pipes 8 into the check valve 15, any grit or heavy particles such as gear and bearing chips, etc., falling 55 into the nipple 12 which in reality is a sump. From there they may be removed by removing the cap 13. This feature eliminates the possibility of their being carried forward and probably get into the cylinders and bearings and score the same.

When the car is running on level ground, or up hill, the ball 16 in the check valve will always remain against the plug 15^a and

will allow free passage of the oil from the pipe 8 to the pipe 18 and thence to the timer 65 case.

When going down any grade with sufficient slant to counteract the reverse slant of the check valve, the ball 16 therein rolls forward by the force of gravity and contacts 70 against the seat 17, thereby closing communication between the pipes 8 and 18.

By having the pipe 18 enter the timer case at the forward end thereof, a supply of oil to the timer gears and every bearing, etc., to 75 the rear of the same is insured.

Thus, from the foregoing description it will readily be seen that I have produced such a device as substantially fulfills the objects of the invention as set forth herein. 80

While this specification sets forth in detail the present and preferred construction of the device, still in practice, such deviations from such detail may be resorted to as do not form a departure from the spirit of the invention, 85 as defined by the appended claims.

Having thus described my invention, what I claim as new and useful and desire to secure by Letters Patent is:—

1. In combination with an internal combustion engine having a transmission casing at the rear end and a timer gear casing at the forward end thereof, an oil pipe screwed at one end to the transmission casing at a relatively high point therein and adapted to 95 receive oil thereinto by the splash created by the gears in the casing, said pipe extending forward on a downward slant and being screwed into the front face of the timer gear casing adjacent the bottom thereof, and 100 means whereby when the vehicle in which the engine is mounted is going down a grade the flow of oil to the forward end of the engine will be automatically stopped.

2. In an oil conveying pipe for gas engines extending from a high point on the transmission casing and sloping down to the bottom of the timer gear case at the forward end of the engine, a means whereby when the vehicle in which the engine is mounted is 110 going down a grade the flow of oil to the forward end of the engine will be automatically stopped, such means including a tubular member interposed in the pipe longitudinally of the engine and having a ball-seat 115 in its forward end, a ball rollable in the tubular member and adapted to contact with the seat, and a plug in the opposite end of the tube and adapted to receive the ball thereagainst, the tubular member having a 120 normal downward slant to the rear and the communicating pipe from the transmission casing being in one side thereof.

In testimony whereof I affix my signature.

ELMER E. WELLS.
